UNITED STATES PATENT OFFICE.

FRANK J. DAVY AND JOSEPH T. NEMACHECK, OF LA CROSSE, WISCONSIN.

POST TOPPER.

Application filed September 29, 1923. Serial No. 665,588.

To all whom it may concern:

Be it known that we, FRANK J. DAVY and JOSEPH T. NEMACHECK, both citizens of the United States, and residents of La Crosse, 5 in the county of La Crosse and State of Wisconsin, have invented certain new and useful Improvements in Post Toppers; and we do hereby declare that the following is a full, clear, and exact description thereof.

10 This invention pertains to a device for trimming the tops of posts, such as fence posts and the like, and has primarily for its object the provision of a simple, inexpensive and efficient device of the above character, 15 which is manually operable and quickly positioned on or detached from the post, thereby trimming the top of the same after it has been set.

A more specific object resides in the provision of a detachable bracket member and a cutting member rotatively and slidably carried thereby and provided with a circular knife adapted to engage the top of a post and shape the same upon suitable manual 25 actuation of the cutting member.

With the above and other objects in view, which will appear as the description proceeds, the invention resides in the novel construction, combination and arrangement of 30 parts substantially as hereinafter described and more particularly defined by the appended claim, it being understood that such changes in the precise embodiment of the herein disclosed invention may be made as 35 come within the scope of the claim.

In the accompanying drawing is illustrated one complete example of the physical embodiment of the present invention constructed according to the best mode so far 40 devised for the practical application of the principles thereof.

Figure 1 is a longitudinal, sectional view taken on the line 1—1 of Figure 2, and

45 Figure 2 is a transverse, sectional view looking down on the line 2—2 of Figure 1.

Figure 3 is a plan view of the cutting member illustrating the preferred structure of knives.

50 Referring more particularly to the accompanying drawing, the form of the invention illustrated consists primarily of an attaching bracket 1 adapted to be secured to the top of the fence post F, indicated by dotted lines, and a cutter member 2 slidably and rotatably carried by the bracket 1.

55 The bracket 1, which is adapted to be posi-

tioned over the top of the post, is designed in the form of a bell provided at its lower edge with an annular band 3 which is connected by means of the vertical arms 4 with the hood top 5, thus forming the openings 6 which allow the operation of the cutter to be viewed, and also permit the shavings to be readily discharged from the work. The hood 5 is provided with a central extension 65 6 which forms a bearing in which the stud 7 is slidably and rotatably journaled.

In that form of the invention illustrated in Figures 1 and 2, the cutting member 2 is of a spherical cup shape provided with a spiral slot 8, to one edge of which is suitably secured a circular knife 9 which projects inwardly of the slot sufficiently to engage the top of the post and perform the cutting operation. The cutting member 2 is threaded, or otherwise suitably secured, to the lower end of the stud 7, which stud is provided at its upper end with a handle 10, to permit the desired manual operation.

For the purpose of detachably mounting 80 the bracket 1 on the top of the post F, the annular band 3 is provided at spaced intervals with thumb screws 11 which engage the post and hold the bracket rigidly during the 85 cutting operation.

From the foregoing it will be seen that a very simple, economical device has been provided by means of which fence posts, or the like, may be quickly topped after they have 90 been set. A further advantage of the device resides in the fact that topping of the posts after they have been set permits an even line to be maintained by reason of the fact that the posts may be set up and cut off to a string line, after which, by means of the 95 present invention, they may be topped in a minimum period of time, the only operation necessary being that of securing the bracket on the top of the post by means of the screws 11, in which position the cutter head 2 engages the flat end of the post. Only a few turns of the handle 10 with a slight pressure downwardly are then required to complete the cutting operation and shaping of 100 the post.

While we have shown and described a one piece circular cutting tool, it will be understood that the same may be constructed in any desired shape and furnished with blades of various contours, without departing from 110 the invention, as, for instance, in Figure 3, wherein we have illustrated the preferred

structure of cutting knives, the same are formed into two sections 12 having slotted connection with the cutter member 2, whereby they may be adjusted inwardly or outwardly by means of the screws 13 threaded into the cutter and having their heads engageable with the outer edge of the knives. This permits a desired takeup for wear.

We claim:—

- 10 A device of the character described comprising a bracket adapted to surround the top of a post, means for securing said bracket on the post, a spherical shaped cup member rotatable and slidably within said

bracket and provided with an arcuate slot 15 extending downwardly at an angle to and outwardly from the axis of rotation of said cup shaped member, and a cutting knife secured to said cup shaped member and conforming to the contour thereof, said knife 20 having its cutting edge extending through said slot.

In testimony that we claim the foregoing we have hereunto set our hands at La Crosse, in the county of La Crosse and State of Wisconsin.

JOSEPH T. NEMACHECK.
FRANK J. DAVY.
